FLAT GRINDING MECHANISM FOR CARDING MACHINES

William Wallace Meredith, Anderson, S. C.

Application June 25, 1937, Serial No. 150,383

1 Claim. (Cl. 51—243)

This invention relates broadly to revolving type flat carding-machines, and more particularly to an improved apparatus for grinding the clothing of the top flats of carding machines; 5 and the invention together with its objects and advantages will be best understood from a study of the following description taken in connection with the accompanying drawings wherein:

Figure 1 is a fragmentary side elevational view 10 illustrating the application of the invention to a carding machine.

Figure 2 is a detail sectional view taken substantially on the line 2—2 of Fig. 1.

Figure 3 is a perspective view of a journal 15 for the grinding roller.

Figure 4 is a perspective view of a slide member and

Figure 5 is a perspective view of a combination fixed guide and lifting plate.

Referring to the drawings by reference numerals it will be seen that in the preferred embodiment of the invention, there is provided a horn bracket 5 fixedly mounted by being bolted or otherwise secured thereto, to the card, and in this connection it will be understood that there 20 are two of these brackets, one attached to each side of the card, and that the other parts mentioned are also in duplicate, one at each side of the card, the grinding roller and flats passing 25 across the top of the card, the supports at both sides being alike. Hence for convenience of description there is shown and described but one horn bracket and associated parts.

As before stated the horn bracket 5 is bolted 30 as at 6 to the side of the card and is firm and stationary. Bracket 5 is provided with an enlarged head provided with a notch 7.

Bolted or otherwise secured as at 8 to one side of the head of the bracket is a substantially 40 U-shaped fixed combination guide and fitting plate indicated generally by the reference numeral 9. The combination element 9 includes the aforementioned U-shaped part 10 bolted as at 45 8 to the head of the bracket 5 and a lifting plate 11 that extends through the slot 7 of the bracket 5 and is provided with a raised protuberant 12 the upper surface of which is convex, and over the surface 12 the curved under surfaces 13 of the flats 14 slide and are raised thereby up into 50 contact with a vertically shiftable guiding plate 15, and against the under surface of which the flats 14 successively bear as they pass forward over the horn 16 of the horn bracket 5.

The guide plate 15 also extends inwardly 55 through the slot 7 in the horn bracket 5 and

projects laterally inwardly from the inner side of a substantially U-shaped slide 16 that has a sliding fit within the guide 10. The sides of the slide 16 are provided with ribs 17 that have a working fit in internal grooves 18 provided 5 therefor in the sides of the fixed guide 10.

A journal 19 for the pintle 20 at one end of the grinding roller 21 has a sliding working fit in the guide 16 and is provided at opposite sides thereof with channels or grooves 22 to accommodate the sides of the slide 16.

Also swivelly connected with the bottom side of the journal 19 is a threaded pin or bolt 23 the lower end of which is accommodated in a suitable opening 24 provided therefor in the 15 bottom of the slide 16.

For adjusting the journal 19 within the slide 16 there is provided an adjusting nut 25 threaded on the pin 23 and having bearing engagement with a substantially hemi-spherical washer 26 20 that accommodates the stem 23 and is interposed between the nut 25 and the bottom of the slide 16. Obviously by turning the nut 25 journal 19 may be secured at the desired position of adjustment within the slide 16, at which time is 25 also affected the desired adjustment of the journal 19 and the guide plate 15, relative to one another. Obviously by so adjusting the guide plate 15 and the journal 19 relative to one another the grinding roller is so adjusted as to give 30 the amount of grinding required. As will be apparent from the following with this device all the wires on all the flats will be ground to the same length it being apparent, that in actual practice, that as a flat 14 passes over projection 12 of the 35 lifting plate 11 the projecting end of the flat 14 engages the under surface of the guide plate 15. If the projecting end of the flat be thick this will result of course in an upward movement of the plate 15 carrying with it the slide 16 and this upward movement of the slide 16 will be transmitted through the nut 25 and stem 23 the journal 19 so that the grinding roll or drum 21 will also move upwardly with the result that the 40 drum will be held at the proper distance from the top of the flat, the wires of which are being ground so that the wires of said flat will be ground to the same length as the wires of preceding and successive flats, it being apparent that the thicknesses of the ends of the flats 14 control the raising and lowering of the grinding roll or drum 21 so that the latter will be positioned at the proper distance from the top face of the flat to the end that a uniform grinding of the 45 flat will result, the grinding of all the flats uni- 50 55

formly being the object of all such devices as involve the subject matter of the present invention.

In connection with the above it will also be understood that the under surface of the guide plate 15 is inclined so as to tilt or heel the flat to give the required formation of the wires being ground, the flat being free to heel by reason of the curved surface of the projection 12 on the shifting plate 11.

It is thought that a clear understanding of the construction utility and advantages of an invention of this character will be had without a more detailed description.

15. What is claimed is:—

In a device for grinding the top-flats of carding machines, and in combination with the grinding roll of the machine, a horn bracket fixed to the machine, a substantially U-shaped guide 20 member fixedly mounted on the horn bracket,

a slide having a working fit between the legs of said guide, a journal for the grinding roll having a sliding fit in said slide and provided with an adjusting screw, and means on the screw co-operable therewith and with the slide for securing the journal at the desired position of adjustment within the slide, said slide being free to move up and down in said guide, a laterally extending guide plate carried by said slide and against the under surface of which one end of the flats successively bear as they pass over the horn of said horn bracket, and a lifting plate projecting laterally from said fixed guide and having an upstanding projection provided with a curved surface and over which the under surfaces of the successive flats bear to be forced thereby into engagement successively with the aforementioned guide plate.

WILLIAM WALLACE MEREDITH. 20
